J. O. McKEAN.
WINDING MACHINE.
APPLICATION FILED JUNE 29, 1911.

1,014,836.

Patented Jan. 16, 1912.

UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MAINE.

WINDING-MACHINE.

1,014,836.

Specification of Letters Patent.

Patented Jan. 16, 1912.

Application filed June 29, 1911. Serial No. 635,950.

To all whom it may concern:

Be it known that I, JOHN O. McKEAN, a citizen of the United States, residing at Westfield, in the county of Hampden and 5 State of Massachusetts, have invented new and useful Improvements in Winding-Machines, of which the following is a specification.

My invention relates to cop winding machines of that class which wind conical cops and wherein the cop is driven by contact with a cop-driving drum or roll. In this type of winding machine, as heretofore constructed, the cop was mounted upon a swinging cop support and rested upon the cop-driving drum, said support yielding upward as the cop grew in size. This swinging cop support was made with a cop holding spindle for rotatably supporting the cop tube or shell and this spindle was free to move toward and from the cop-driving drum with the cop support, and in some instances was free to tilt or rock laterally to allow the cop to fit itself to the cop driving drum. But 25 in all cases the cop has heretofore always been so supported during the winding operation that it was held pressed against the driving drum with uniform pressure throughout its length.

My invention has for its object to provide an improved winding machine of the character specified and it consists in providing the machine with a cop support which is not only movable toward and 35 from the cop-driving roll and constructed so as to permit the cop to rock laterally on an axis perpendicularly tangential with relation to the axis of the cop-driving drum so that the cop is free to fit itself to the driving drum, but which is also constructed so as to hold one end of the cop more forcibly against the driving drum than the other end thereby causing the cop to be more compactly wound at that end than at the opposite site end.

In the best form of my invention the cop support is a swinging arm comprising two main members consisting of a hub pivotally supported so as to swing on an axis parallel 50 with the cop-driving drum, and a cop-holding lever which is pivotally mounted on the hub member so as to turn on an axis crosswise of the axis of the hub and extending tangentially with relation to the cop-driving drum and preferably intersecting the

axis of the cop near the middle of the latter. This cop-carrying lever comprises two arms, one at one side of the last-mentioned axis for holding the cop and the other at the opposite side of said axis carrying a 60 counterbalance weight or the like which yieldingly holds the cop against and fits it to the driving drum with one end of the cop held more snugly against said drum than the other.

36

Other features of my invention are hereinafter pointed out.

In the accompanying drawings, Figure 1 is a perspective view of a portion of a cop winding machine embodying one form of 70 my invention; and Figs. 2 and 3 are details hereinafter described.

Having references to the drawings 3 represents the hub member of the cop support of my improved winding machine and 4 the 75 lever cop-carrying member thereof. The hub 3 is made with a forwardly extending arm 5 provided at its ends with a socket 6 within which is swiveled a stud 7 forming part of the cop-carrying lever 4. The forward end of lever 4 is provided with the usual cop-holding spindle 8 adjustably mounted thereon and adapted to hold a conical cop tube or shell 9 against a driving drum 10 fixed to the usual continuously 80 driven drum carrying shaft 11. The hub 3 is rotatably mounted on a rod or shaft 12 forming a part of the frame of the machine whose axis is parallel with the axis of the drum 10, while the stud 7 and socket 6 are 85 arranged so that the axis of stud 7 extends crosswise of rod 12 and intersects the axis of the cop-holding spindle 8 about midway between the ends of the cop shell or tube 9. The lever 4 has two arms 4^a and 4^b integral 90 with stud 7 and its arm 4^a is disposed at one side of the axis of said stud, while the other arm 4^b is disposed at the opposite side thereof and carries a counterbalance weight 14 secured to said arm by a screw 15 so that it 100 may be adjusted toward and from stud 7.

In winding conical cops there is a tendency for the larger end of the cop to increase in size at a more rapid rate than the smaller end and consequently, the pressure 105 upon the smaller end of the conical cop tends to decrease, and that end has not heretofore been so well compacted, as it should be compacted to the same degree as the larger end. This resulted in imperfections 110

in the winding which I obviate by the construction described above.

In winding a cop upon my improved machine the counterbalance weight 14 is adjusted so as to hold that portion of the cop extending from the intersection of the axes of stud 7 and spindle 8 to the small end of the cop more forcibly against the driving-drum 10 than the other end of the cop. At the same time, however, this weight coöperates with the weight of the other parts of the cop support to yieldingly hold the cop as a whole in driving contact with the drum 10. As a result of the relatively greater pressure at the smaller end of the cop the convolutions at said smaller end are compactly laid together thereby increasing the tendency of the larger end to grow faster than the smaller end and increase the conicity of the cop. At the same time the capacity of the cop holder to rock on the axis of stud 7 permits the cop to at all times fit itself perfectly to the driving-drum so that uniform contact is maintained between the cop and its driving-drum throughout the length of the cop during the winding operation.

The hub 3 is made with an integral depending arm 16 pivotally connected at 17 with a forwardly extending rack bar 18 that rests upon an arm 19 loosely mounted on a rod 20 but connected by lugs 22 with a frame 21 pivotally supported on rod 20. The bar 18, arm 19, rod 20, frame 21 and lugs 22 are parts of the usual stop motion mechanism which acts as usual to pull rack bar 18 forward and thereby swing the cop support up to lift the cop off from the drum 10 and stop the winding operation when a thread breaks or the winding operation is finished. During the winding operation the rack bar 18 is, as usual, free to move forward relatively to arm 19 as the cop grows in size.

When the cop is swung up, either by the stop motion or by hand, it is obvious that the effect of weight 14 is to throw the point of the cop downward. In order to hold cop support 4 against excessive swinging movement on the axis of stud 7 when said support is thus swung upward, I provide a pair of stops 22 and 23 on the cop support, the former coöperating with the top of arm 5 to limit the downward swing of the lever 4, and the latter coöperating with the under side of arm 5 to limit the upward swing of said lever. Sufficient lost motion is provided between the stops 22 and 23 and arm 5 to provide for free control of the lever 4 by weight 14, and to permit the cop to fit itself to the drum, during the winding operation. As herein shown the stops 22 and 23 are lugs on a plate 24 fastened by means of a screw 25 to the rear of lever 4.

ing a cap 6* yieldingly clamped upon stud 7 by means of a screw 26 acting through a spring 27. By constructing the socket in this fashion and properly adjusting screw 26 the socket may be caused to frictionally grip the stud 7 so as to regulate and control the swinging movements of the cop holding lever 4 on the axis of stud 7.

What I claim:—

1. In a winding machine the combination with the driving drum, of a cop support for yieldingly holding a conical cop against said drum, said support comprising means to provide for lateral rocking movement of the cop upon an axle perpendicularly tangential with relation to the axis of the driving drum, and means for holding one end of the cop more forcibly against the driving drum than the opposite end. 75

2. In a winding machine the combination with the driving drum, of a cop support for yieldingly holding a cop against said drum, said support comprising means to provide for lateral rocking movement of the cop upon an axis passing through the cop intermediate its ends and which is perpendicularly tangential with relation to the axis of the driving drum, and means for holding the smaller end of the cop more forcibly against the driving drum than the 95 larger end. 85

3. In a winding machine the combination with the driving drum, of a cop support for yieldingly holding a cop against said drum, said support comprising means to provide for lateral rocking movement of the cop upon an axis which intersects the axis of the cop midway between the ends of the latter and which is perpendicularly tangential with relation to the axis of the driving 105 drum; and a weight or the like for holding the smaller end of the cop more forcibly against the driving drum than the larger end. 100

4. In a winding machine the combination with the cop driving drum, of a cop support comprising two members consisting of a hub pivotally supported on an axis parallel with the driving drum and a cop-holding lever pivotally mounted on the hub so as to 110 rock laterally on an axis perpendicularly tangential to the axis of the driving drum and which intersects the axis of the cop intermediate the ends of the latter, said lever being made up of two arms one at one 115 side of the last-mentioned axis provided with a cop holding spindle, and the other arm at the opposite side of said axis provided with a counterbalance weight. 120

5. In a winding machine the combination with the cop driving drum, of a cop-support comprising two members consisting of a hub pivotally supported on an axis parallel with the axis of the driving drum and

- the hub so as to rock laterally on an axis perpendicularly tangential with relation to the axis of the driving drum and which intersects the axis of the cop intermediate 5 the ends of the latter, said lever being made up of two arms one at one side of the last-mentioned axis provided with a cop holding spindle, and the other arm at the opposite side of said axis provided with 10 a counterbalance weight; stop motion devices connected with the hub of the cop, and means on the hub to limit the lateral rocking movements of the lever member of the cop support.
- 15 6. In a winding machine the combination with the driving drum and stop motion devices thereof, of a cop-support for yieldingly holding a cop against said drum comprising two members consisting of a hub 20 pivotally supported on an axis parallel with the axis of the driving drum and a lever pivotally connected with the hub so as to swing laterally on an axis perpendicularly tangential to the axis of the driving drum 25 and which intersects the axis of the cop
- between the ends of the latter, said lever being made up of two arms one of which is at one side of the last-mentioned axis and provided with a cop holding spindle, and the other at the opposite side of said axis and provided with a counterbalance weight; 30 a pair of stops on the cop supporting arm of the lever coöperating with the hub to limit the rocking movements of said lever, and an arm on the hub connected with the 35 stop motion devices of the machine.
7. In a winding machine the combination with the driving drum, of a cop support pivoted to swing in two planes and carrying an adjustable weight to yieldingly press the 40 cop against the driving drum by swinging in one plane and by adjustment in the other plane to distribute such pressure in varying measure between the ends of the cop.

Signed by me at Westfield, Massachusetts, 45 this 27th day of June, 1911.

Correction in Letters Patent No. 1,014,836.

It is hereby certified that in Letters Patent No. 1,014,836, granted January 16, 1912, upon the application of John O. McKean, of Westfield, Massachusetts, for an improvement in "Winding-Machines," an error appears in the printed specification requiring correction as follows: Page 2, line 80, for the word "axle" read *axis*; and that the said Letters Patent should be read with this correction therein that the same may conform to the record of the case in the Patent Office.

Signed and sealed this 13th day of February, A. D., 1912.

Acting Commissioner of Patents.

- the hub so as to rock laterally on an axis perpendicularly tangential with relation to the axis of the driving drum and which intersects the axis of the cop intermediate 5 the ends of the latter, said lever being made up of two arms one at one side of the last-mentioned axis provided with a cop holding spindle, and the other arm at the opposite side of said axis provided with 10 a counterbalance weight; stop motion devices connected with the hub of the cop, and means on the hub to limit the lateral rocking movements of the lever member of the cop support.
- 15 6. In a winding machine the combination with the driving drum and stop motion devices thereof, of a cop-support for yieldingly holding a cop against said drum comprising two members consisting of a hub 20 pivotally supported on an axis parallel with the axis of the driving drum and a lever pivotally connected with the hub so as to swing laterally on an axis perpendicularly tangential to the axis of the driving drum 25 and which intersects the axis of the cop
- between the ends of the latter, said lever being made up of two arms one of which is at one side of the last-mentioned axis and provided with a cop holding spindle, and the other at the opposite side of said axis and provided with a counterbalance weight; 30 a pair of stops on the cop supporting arm of the lever coöperating with the hub to limit the rocking movements of said lever, and an arm on the hub connected with the 35 stop motion devices of the machine.
7. In a winding machine the combination with the driving drum, of a cop support pivoted to swing in two planes and carrying an adjustable weight to yieldingly press the 40 cop against the driving drum by swinging in one plane and by adjustment in the other plane to distribute such pressure in varying measure between the ends of the cop.
